The ornamental design for a tape measure, as shown and described.

DESCRIPTION

FIG. 1 is a perspective view of a tape measure showing my new design wherein the rule is partially extended; FIG. 2 is a second perspective view opposite of that which is shown in FIG. 1, wherein the rule is not extended;

FIG. 3 is a side view of a tape measure showing my new design;

FIG. 4 is an opposite side view of that which is shown in FIG. 3;

FIG. 5 is a bottom view of that which is shown in FIG. 4;

FIG. 6 is a top view of that which is shown in FIG. 5; FIG. 7 is a front view of that which is shown in FIG. 6;

FIG. 8 is a rear view of that which is shown in FIG. 7;

and,

FIG. 9 is an exploded view.
